To Benjamin Hamblot, Portland, Maine

Letter Patent

This schedule of record to witness Letter Patent and making part of the same containing a description in the words of the said Benjamin Hamblot himself of his improvement in the machine for making brick and tile

To all to whom these presents shall come

Be it known that I the said Benjamin Hamblot of Portland in the County of Cumberland & State of Maine have invented a new and useful improvement in the manner of making and constructing machinery for making mortar and striking the same into bricks & tiles by horse power or any other power and that the following is a full & exact description of the construction and operation of the said machine as invented and improved by me - 1. I make a frame five & half feet high & three & half feet square for striking four bricks in a mould & four feet square for striking six bricks in a mould. I have three sets of girts one near the top middle and bottom. Then I plank it all round & spike them together. On the middle girt I lay one cross girt from right to left. On these girts I lay a flooring of plank which makes the bottom of the mortar pit. In the center of this floor I make a round hole four inches deep and four inches diameter to receive the lower end of the grinding shaft. Then I lay another cross girt from ~~the~~ right to ~~the~~ left on the upper set of girts and make a large hole through it direct by over the hole in the bottom through which I pass the grinding shaft. On two or more of the sides I set in a row of ^{steel} wooden pins horizontally four inches more or less apart from the bottom to near the top. These pins may be eighteen inches long more or less. On this is mortised a frame may be made in two parts. The bottom part of it in which the striking apparatus is placed may be about two feet high. The parts of timber may be set more or less with two sets of girts. The upper tier of girts whereon the floor of the mortar box is placed should be faced with

the top of the party. The timbers which make the place for the false moulds, should be put under these girts. The travel ways for the carriage should bear the lower tier of girts. Then the upper part of the frame for the mortar box may be made of joists of the same bigness as the lower part & planked all round. & set on the under part and fastened on by strong hasps or spiked on. The bigness of it may be regulated as above do with according to the number of bricks to be struck at a time.

2. Then I have a strong shaft which I set perpendicularly in the mortar Box. The lower end is standing in the mortise aforesaid and the upper end passing up through the cross girt about two feet above it. This shaft is set with two rows of pins horizontally & of a piece and long enough to reach nearly a foot off the mortar Box and as the shaft turns round these pins pass between the pins aforesaid set in the side of the box & thereby the mortar is ground & made for the Bricks. On the top of this shaft a sweep is framed after the common manner of the Cyder Mill by which a horse turns the machine. — 3. In front of the bottoms an opening is made about four inches deep and a little longer than the length of the brick moulds through which the mortar passes from the mortar box to fill the moulds, as the bricks are struck by the operation of the machine. 4. On the under side of the girts on which the floor of the mortar box is laid I put in two timbers four inches square more or less as may be necessary & fasten them on strong. These two timbers should project out in front about one foot and have a like place framed in the end. These two timbers should be about two feet apart when four bricks are struck at once & about three feet apart when six bricks are struck at once. In this way the place is made for the false moulds through which the mortar is forced on to the brick moulds. This place for the false moulds is made barreling all round and the false moulds are made barreling as as aforesaid to suit. By this barrel shape the false moulds are kept in their place. These timbers also serve to confine the carriage on the upper side which carries the moulds in and out when striking & making bricks.

5. These false moulds, or tubes, have four or six openings according to the number of bricks the moulds carry and corresponding nearly in

size with the brickmoulds, but a little smaller all round. The openings in the false moulds in each aperture should be bevelled on each side & end upwards, so as to hold the mortar from dropping down between the brickmoulds, and passing in and out. — 6. I make three sides, of a crib or box of Plank eight inches high which stands round the aperture (No 4.) in which the false moulds are placed and is a little larger than that aperture. The two inner ends of the before named pieces of this crib pass into two mortices in the front side of the mortar box. This crib receives the mortar from the mortar box aforesaid through the opening in front of the mortar box ready to be forced down through the false moulds into the brickmoulds & may properly be called the receiver. This crib is kept in its place by two strong pins, standing in front of it or by hasps — 7. A dasher or follower. Works in this receiver made as follows. A thick piece of plank is filled to the size of this receiver. Then another piece of plank six inches wide more or less is put edgewise upon the follower & flesh with inner edge. This part of the dasher when the dasher is down closes the opening in front by which the mortar passes from the mortar box into the receiver when the mortar is not wanted; and this is done every time the dasher is pressed down to fill the moulds. And when the dasher is raised the fastenings are opened and the mortar again let into the receiver. and soon continually. Close to the upright part of this dasher in the middle a piece of plank ten inches wide is framed in with a tenon at each edge and may be about three feet long. The upper end of this handle passes through a guide to keep the motion steady & perpendicular. The handle of this dasher also passes free through a mortice in the box which works it & works on this mortice on a pin.

8. On the left side of the machine in front a box post stands perpendicular three feet eight inches long more or less & is put loose on to a stout pin in that corner post of the machine.

9. The left end of the upper lever is set loose in a mortice in the upper end of this box post & held in by a pin. This iron reaches horizontally across the machine and about two feet beyond. When the machine is

in operation the dasher is worked up and down by this lever & another. This shal lever is fit into a ~~ten~~ mortise in the lower end of the ~~ten~~ post aforesaid and held in by a pin in the same manner that the other lever is & runs parallel with below the carriage aforesaid & may be of the same length with the upper lever. These levers are connected together on the right side of the receiver by a piece of wood 4 by 1 inch & parallel with the ~~ten~~ post aforesaid. This piece which I call a hauling brace passes ~~ten~~ through a mortise in each lever & is held in each mortise by a pin. The use of this lever is to tread upon with the foot in bring down the dasher, in filling the moulds with mortar which is much easier than to press the upper one down with the hand. Both can be used together if necessary. — 10. Two pieces of joist are fastened onto the lower girts for ways for the carriage to travel in and out on when the machine is in operation. Two friction Rollers are set in each girt with one shaped edge. These ways must be so placed as to bring the upper side of the carriage & moulds close under the false moulds so as to strike the upper sides of the bricks. — 11. Then I make a carriage to travel on the ways aforesaid three feet long & two & quarter feet wide when four bricks are struck at a time & three feet wide when six bricks are struck at a time. This carriage is made of two pieces of plank set up edgewise & two feet of the back part of the carriage is floored over with boards. The way pieces and floor should be five inches thick. These way pieces should come right over the friction Rollers (No. 10.) Then cast iron ways with a one grooving should be let into these wooden ways so as to come directly over those friction Rollers & travel on them when the carriage travels in and out. The front part of this carriage should be cut down enough to let the brick mould & strike board in flesh with the floor. The plank should be about ten inches wide. Then a small trough should be made in front of the moulds into which to wipe the clay when striking. The use of the flooring of the back part of the carriage is to keep the mortar from sagging down while the carriage is running in and out. On the underside of this flooring a cast iron toothed rack one & a half feet long is placed and fastened on.

10. The cog wheel option makes diameter one or 1/2 which makes into the back of mine a portion an iron staff of proper size say 1/4 in. wide square. This staff goes through the machine from right to left below the front post & rests in an iron bed on each post. The right end of this staff comes out about 1/2 in. higher at the machine and has a crank fitted onto it by which it is worked when the wheel turns the carriage round off. A pulley is put on to this staff close up to the machine diameter inches in diameter. A nut on the left end of this staff holds it from slipping sideways.

11. A rope is fastened to this pulley passes over another pulley upon the side of the machine & the other end goes down & is fastened onto the back lever. The use of this rope is to raise the following when the moulds are run out and thereby to open the receiver so that it may be filled with water and ready for the next filling of the moulds.

12. I have now described the several parts of my machine & their functions. I do not claim the whole as my own invention, though it was necessary to describe them all in order to describe what I claim as my own invention and describe the operation of the whole machine. The parts which I claim are the following. The improvement on the dasher by working it and steadyng ^{it} by the staff & the guide through which the handle passes. The lever, staff and the levers & the manner of connecting them together and with the staff and their operation; The manner of connecting the shaft of the cog wheel & the levers with the rope passing up over the pulley. The application of the sack and cog wheel to the carriage to move it out and in. The method moulding and striking the bricks crosswise in stead of length wise which preserves the bricks in better shape than the mould and strike them lengthwise & they may be strike in the way. To the other parts of the machine I lay no claim except to use them with those that I do claim.

13. A flat piece of wood should be laid on the left front post so as to bring the lever post forward a little and a flat piece of wood should also be laid onto the right front post for the levers to bear against in the course up and down. 14. The use of the line attached to the pulley on the shaft of the cog wheel and passing over the pulley on the

9298X

right side of the right hand front foot & down to the lower beam is to
cover the dasher when the carriage is run out. Style may be made in
this machine by altering the shape of the moulds and galleries moulds.
In testimony that the above is a true specification of my said improve-
ment as above described I have hereunto set my hand this twenty ninth
day of April in the year of our Lord One thousand Eight hundred
and thirty five.
